HIGH-FREQUENCY GENERATOR

Angelo Montani, Woodhaven, N. Y., assignor to
 Automatic Electric Laboratories, Inc., Chicago,
 Ill., a corporation of Delaware

Application September 24, 1945, Serial No. 618,352

3 Claims. (Cl. 250—164)

1

The present invention relates to high frequency generators, and particularly to high frequency generators of the electron beam type.

Previously proposed electron beam high frequency generators have employed various forms of commutators which are scanned by an electron beam. Interception of the beam by alternate commutator segments produces oppositely directed impulses in a resonant circuit coupled to the commutator, thereby sustaining oscillations in the resonant circuit when the number of pairs of commutator segments scanned per second is equal to the natural frequency of the resonant circuit. In these prior art devices the frequency and waveform of the output voltage is determined largely by the nature of the load circuit. When the circuit Q of the resonant circuit is very high, as it is in the case of a cavity resonator, a relatively pure sinusoidal waveform will be produced in the output circuit.

The principal object of the present invention is to provide a new type of high frequency generator, or frequency multiplier, wherein the frequency and waveform of the output voltage is not dependent upon circuit constants, but is instead determined by the physical construction of the generator.

Another object of the invention is to provide an electronic high frequency generator which is adapted to produce an output current having any desired waveform.

Still another object of the invention is to provide an improved means for controlling the generation of high frequency currents by lower frequency currents.

Briefly, these objects are accomplished by providing a specially shaped collecting electrode in a tube structure similar to a conventional cathode ray tube. The collecting electrode is cyclically scanned by an electron beam and is shaped so that the length of the path traversed by the electrons in the beam varies throughout the scanning cycle. This variation in beam length is related to the scanning rate and to the electron velocity so as to produce currents having any desired frequency and waveform in an output circuit connected to the collecting electrode.

The invention will be better understood from the following description when considered in conjunction with the accompanying drawing, in which:

Fig. 1 discloses one form of the invention in which the electron beam is cyclically deflected along a rectilinear scanning path;

Fig. 2 is a modification of Fig. 1 in which the

2

electron beam is deflected so as to scan a circular path on a ring-shaped collecting electrode;

Fig. 3 illustrates the waves produced in the electron beam when a deflecting voltage of recurrent triangular waveform is applied to the deflecting electrodes of the tube shown in Fig. 1; and

Fig. 4 illustrates the waveform of the current flowing to the collecting electrode of the tube shown in Fig. 1 for different angular positions thereof when the electron beam is deflected as shown in Fig. 3.

Referring to Fig. 1 of the drawing, there is shown a cathode ray tube having the conventional heater 1, cathode 2, and beam forming electrodes 3, 4 and 5, all of which are energized by a suitable battery 6, or the like. The pencil-like electron beam, indicated by the broken line 7, passes between a pair of deflecting electrodes 8, which are positioned on opposite sides of the beam axis. It is to be understood that the equivalent magnetic deflecting coils or other suitable means may be substituted for the electrostatic deflecting electrodes, if desired. The electron beam is caused to scan a rectilinear path by applying an alternating voltage from a suitable source, such as a control oscillator 9, to the deflecting electrodes 8.

The collecting electrode 10 is a plate which is positioned in angular relation to the beam axis. The upper and lower portions of the plate are formed at an angle to the center section, as indicated. The collecting electrode is connected to battery 6 through a radio frequency choke 11, across which the output voltage appears when the tube is in operation.

In considering the operation of the tube it will first be assumed that the alternating voltage applied to the deflecting electrodes 8 by the control oscillator 9 is of triangular waveform and has a period several times shorter than the transit time of the electrons from the deflecting electrodes to the collecting electrode. Triangular waves will then be produced in the beam as illustrated in Fig. 3. The electrons all travel in straight lines at the same velocity causing these waves to travel towards the right of the figure. It is obvious that if the collecting electrode was a plane surface located perpendicular to the beam axis, as at A', that the number of electrons impinging on the collecting electrode per unit of time would remain constant. The resulting current in the output circuit is illustrated by the straight line A in Fig. 4. If the collecting electrode were rotated about an axis perpendicular to

the beam axis, and to the scanning path, to the position C' a large number of electrons would impinge on the collecting electrode simultaneously, following which electrons would impinge thereon at one-half the rate as when the collecting electrode occupied the position A'. The resulting output current is shown by curve C in Fig. 4. If the collecting electrode were rotated to an intermediate position such as B' in Fig. 3 the output current would follow a curve such as B in Fig. 4. If a saw-toothed voltage wave, of which one side is approximately perpendicular to the wave axis, is applied to the deflecting electrodes in place of a triangular voltage wave, an output current similar to curve C will be obtained with the lower value of current reduced to zero. The effect of a commutator may thus be obtained, but with the advantage that all of the energy contained in the beam is utilized.

In the preceding paragraph it was assumed that a triangular voltage wave was applied to the deflecting electrodes for simplicity of explanation. If the deflecting voltage is sinusoidal then sinusoidal waves will be produced in the beam similar to the triangular waves shown in Fig. 3. These waves are not true sinusoids, of course, since the amplitude increases progressively with the distance along the beam axis. In this case the output current will still be constant if the collecting electrode is a plane surface positioned as at A' of Fig. 3. If the collecting electrode was rotated to the position C' an output current similar to that shown in curve C of Fig. 4 will be obtained, but with rounded corners. With the collecting electrode rotated to the position B' the rounding of the corners in the output wave would be more pronounced and would result in a wave closely resembling a sinusoid. The shape of the collecting electrode may be varied to produce any desired waveform in the output current. If desired, the deflecting electrodes 8 may be coupled to the output circuit rather than to oscillator 9 in order to use the tube as a self-excited oscillator.

Instead of using a collecting electrode having a single plane surface, the invention contemplates the use of a collecting electrode having a plurality of intersecting plane surfaces which are successively scanned by the electron beam as illustrated in Fig. 1. For each scanning cycle the output current will pass through a number of cycles equal to the number of plane surfaces in the collecting electrode. Thus with the collecting electrode shaped as in Fig. 1 an output current having three times the frequency of the deflecting voltage will be obtained.

In order to provide a greater frequency multiplication factor the collecting electrode may be made in the form of a corrugated ring 12 as shown in Fig. 2. An additional pair of deflecting electrodes 13 are provided for deflecting the electron beam perpendicular to the plane of the drawing. The electron beam 7 is caused to scan a circular path by applying deflecting voltages which are in phase quadrature to the two sets of deflecting electrodes. By way of example, the desired phase relation may be achieved by connecting a suitable 90° phase-shifting network 14 between the oscillator 9 and the deflecting electrodes 8. In this case instead of producing waves in the beam 7 a conical spiral will be formed thereby. If the collecting electrode was a plane ring shaped electrode located perpendicular to the beam axis, the output current would again be constant. Due to the corrugations in the col-

lecting electrode and the transit time required for the electrons to travel a distance equal to the depth of these corrugations, the current flowing through the output circuit will be undulating. Each time that the beam 7 makes one revolution the output current will pass through a number of undulations corresponding to the number of corrugations in the collecting electrode, or ten in the present instance. The shape and spacing of the corrugations may be varied to produce any desired output waveform. The potentials applied to the accelerating electrodes of the beam forming gun must be adjusted to provide an electron velocity which is properly related to the depth of the corrugations in the collecting electrode and the scanning rate of the beam in order to obtain the optimum conditions for maximum output.

While what is now considered to be the preferred form of the invention has been illustrated, it is to be understood that numerous modifications may be incorporated therein without departing from the true spirit and scope of the invention as defined in the subjoined claims.

What is claimed is:

1. In a high frequency generator, means for producing a beam of electrons, means for causing said beam to cyclically scan a fixed path, a collecting electrode disposed in said path, said collecting electrode being shaped so as to cause the transit time of the electrons impinging thereon to cyclically increase and decrease during each scanning cycle to thereby produce a current flow having a waveform dependent on the shape of said collecting electrode.
2. In a wave producer, a source of electrons, means for deriving a beam of electrons from said source, means for rotating said beam, a collecting electrode disposed in the path of said rotating beam, said collecting electrode being shaped so that the distance traversed by the electrons in said beam between said source and the point where they impinge on said collecting electrode alternately increases and decreases in a continuous and periodic manner during rotation of said beam.
3. In a frequency multiplier, a source of electrons, means for deriving a beam of electrons having a constant velocity and uniform density from said source, means for causing said beam to cyclically scan a fixed path, a collecting electrode disposed in said path, said electrode being shaped so as to cause the length of said beam, measured from said source to the point at which the electrons impinge upon said electrode, to increase during a portion of each scanning cycle and to decrease during another portion of each scanning cycle to thereby cyclically vary said beam length a plurality of times during each scanning cycle, whereby a current having a frequency which is a multiple of the scanning frequency is produced in said collecting electrode.
